PERCUSSIVE TOOL BLOWING DEVICE

William A. Smith, Jr., North Arlington, N. J.,
assignor to Worthington Pump and Machinery
Corporation, New York, N. Y., a corporation of
Virginia

Application May 10, 1934, Serial No. 724,889

2 Claims. (Cl. 121—10)

This invention relates to percussive tools, such as rock drills of the hammer piston type, and more particularly to a blowing device for blowing or cleansing the drill hole.

5 An object of the present invention is to provide in a pressure operated hammer piston tool, means whereby pressure fluid used to operate the tool may be selectively admitted to the front end of the tool for passage through the hollow drill 10 steel for cleansing the drill hole, and also to provide means for balancing the hammer piston during the blowing operation.

With these and other objects in view as may appear from the accompanying specification, the 15 invention consists of various features of construction and combination of parts, which will be first described in connection with the accompanying drawing showing a longitudinal section through a percussive tool embodying the blowing device, and the features forming the invention will be specifically pointed out in the claims.

Referring more particularly to the drawing, the improved rock drill comprises a cylinder 1 in which the hammer piston 2 reciprocates. The 25 hammer piston 2 has an extension 3 formed thereon which strikes the drill bar or working tool 4 for operating the tool. The extension 3 is fluted as shown at 5, and it is customary in percussive tools of this type to permit rotation of the working tool 4 through the medium of the chuck mechanism 6, by rotation of the piston 3 through the medium of the rifle bar rotating mechanism 7. The rifle bar rotating mechanism 7 is well known in the art and since it forms no part of 35 the present invention it will not be specifically described herein.

The hammer piston 2 is reciprocated in the cylinder 1 by pressure fluid such as compressed air and the delivery of the pressure fluid while 40 the distribution of the pressure, to cause proper reciprocation of the piston 2, is controlled by means of the distributing valve 9.

The cylinder 2 has an exhaust port 10 therein which opens to atmosphere and which is controlled by the piston 2. The exhaust port 10 permits the exhausting of the air or pressure fluid from the ends of the cylinder 1 at the proper times during the operation of the tool, as is customary in percussive tools of the hammer piston type.

The cylinder 1 has a front cylinder washer 11 mounted therein, the lower end of which receives the section 12 of the chuck mechanism 6.

At times, it is desirable to clean the drill hole 55 being drilled by the drill bar 4, and to provide for

such cleaning a blowing passage 14 is formed in the cylinder 1. The blowing passage 14 has communication through a branch passage 15 with the throttle valve 8 so that when the throttle valve 8 is in the position shown in the drawing, the live or unused pressure fluid will be cut off from delivery to the distributing valve 9 and directed upwardly through the blowing passage 14. From the blowing passage 14 the pressure fluid passes, through the branch passage 16 into the annular channel 17. As shown in the drawings, the annular channel 17 is formed part in the front cylinder washer 11 and part in the section 12 of the chuck mechanism. Transverse port or ports 18 communicate with the annular channel 17 and open into the chamber 19 formed in the chuck mechanism outwardly of the end of the piston extension 5, so that the blowing air will pass through the blowing passage 14, branch passage 16 and into the annular channel 17 from 20 which some of it will pass through the port or ports 18 into the chamber 19. From the chamber 19 the majority of the blowing air will pass out through the bore 20, in the drill bar 4 or other working tool for the purpose of blowing out 25 and cleansing the drill hole.

Some of the blowing air will pass upwardly through the flutes 5 in the piston extension 3 into the cylinder 1 forwardly of the piston 2.

For the purpose of preventing movement of the piston during the blowing operation, that is, for the purpose of balancing the piston against the pressure of the blowing air which passes into the cylinder through the flutes 5, a return blowing passage 21 is formed in the cylinder 1. The return blowing passage 21 has communication with the annular channel 17 through a branch passage 23 and its upper end opens out through a port 24 into the cylinder 1 on the opposite side of the exhaust port 10 from the annular channel 17 40 and consequently on the opposite side of the exhaust port from the portion of the cylinder into which the blowing air passes through the flutes. The port 24 is of such area, together with passages 21 and 23, that the blowing air delivered 45 to the rear end of the cylinder on the opposite side of the piston 2 from the portion of the cylinder into which the blowing air enters, will act to balance the piston 2 and hold it against movement during the blowing operation.

When pressure fluid is being delivered to the rear end of the cylinder 1 and the piston 2 is moving forwardly, as the piston uncovers the port 24 a puff of blowing air will pass through the port 24, down through the passages 21 and 23 through 55

the annular channel 17 and ports 18 and into and through the bore 20 of the working implement or drill bar 4 for blowing the cuttings away from the drill. This blowing puff of pressure fluid 5 may be sufficient to cleanse the drill hole when the hole is shallow but when the hole becomes deep it will only be sufficient to temporarily cleanse the cuttings from about the bit.

Summing up generically; when the throttle 10 valve 8 is moved to deliver air to the blowing passage for the purpose of blowing or cleansing the hole, this air or pressure fluid will pass through the blowing passage 14 into the annular channel 17 from which the major part of the air 15 under pressure will pass into the chamber 19 and out through the bore 20 in the working tool 4, thoroughly blowing or cleansing the drill hole. Part of the air will leak through the flutes 5 into the forward end of the cylinder forwardly of the 20 piston 2. To counterbalance this leakage of blowing air, a certain amount of the blowing air will pass through the return blowing passage 21 and port 24 into the cylinder on the opposite side of the piston, thus substantially equalizing the 25 pressure on both sides of the piston and holding it against movement during the blowing operation.

It will be understood that the invention is not to be limited to the specific construction or arrangement of parts shown but that they may 30 be widely modified within the invention defined by the claims.

What is claimed is:

1. In a percussive tool, the combination, of a 35 cylinder having a main exhaust port, a piston in the cylinder controlling the exhaust port, a throttle valve for controlling the delivery of operating pressure fluid to the drill, a chuck structure in

the forward end of the cylinder, an extension on the piston having flutes therein, a working implement acted upon by said hammer piston and having a bore, a blower passage leading from said throttle valve to said chuck structure and controlled by said throttle valve for supplying pressure fluid to said working implement and through said flutes to the cylinder forwardly of the exhaust port, and a return blower passage in said cylinder opening into the cylinder rearwardly of 10 said exhaust port for conveying pressure fluid to the cylinder for balancing said piston during the blowing of the drill hole, said return passage opening into said cylinder at a point whereby the cylinder will be cut off from exhausting communication with atmosphere during the return of blowing air thereto.

2. In a percussive tool, the combination, of a cylinder having a main exhaust port, a piston in the cylinder controlling said exhaust port, a 20 chuck structure in the forward end of the cylinder, a working implement acted upon by said hammer piston and having a bore therein, said cylinder provided with a return blower passage 25 and a port opening into the cylinder and passage, 30 said passage having communication with the bore in said working implement, said port being covered and uncovered by the piston whereby at predetermined times a puff of pressure fluid will be delivered through said port and passage and into and through the bore of said working implement, said port located with respect to said main exhaust port so that during the return of blowing air to the cylinder through the port the cylinder will be cut off from exhausting communication with the atmosphere.
